UNITED STATES PATENT OFFICE.

HENRY HAUCK, OF NEW YORK, N. Y.

DESIGN FOR A PICTURE FRAME.

Application filed October 25, 1927. Serial No. 23,877. Term of patent 3½ years.

To all whom it may concern:

Be it known that I, HENRY HAUCK, a citizen of the United States, residing at 115 Vermilyea Avenue, New York city, county and State of New York, have invented a new, original, and ornamental Design for Picture Frames, of which the following is a specification, reference being had to the accompanying drawing, forming part thereof.

The single figure is a perspective view of the picture frame.

What I claim is:

The ornamental design for a picture frame substantially as shown.

HENRY HAUCK.
